Primary Examiner—Brian N Vinson

(57) **CLAIM**

The ornamental design for a shower caddy base, as shown and described.

DESCRIPTION

In a preferred embodiment the nature of this product is a lower section of a shower caddy that can be used to support items from a showerhead when assembled to a hanger.

FIG. 1 is a front elevational view of our new design;

FIG. 2 is a right, bottom, frontal perspective view thereof;

FIG. 3 is a bottom plan view thereof;

FIG. 4 is a top plan view of thereof;

FIG. 5 is a right side elevational view thereof, the left side elevational view thereof being the mirror image thereof; and,

FIG. 6 is a rear elevational view thereof.

The broken line representation of support ribs in FIGS. 2 & 3, molding gate marks and pin marks in FIGS. 3 and 4, and cup bottom supports in FIGS. 2-4, are for purposes of illustration only, and form no part of the claim.
